CLAIM

The ornamental design for a smokeless ashtray, as shown and described.

DESCRIPTION

FIG. 1 is a front side perspective view of a smokeless ashtray showing my new design;

FIG. 2 is a front elevational view thereof;

FIG. 3 is a side elevational view thereof; the opposite side being a mirror image thereof;

FIG. 4 is a top plan view thereof;

FIG. 5 is a rear elevational view thereof opposite to that shown in FIG. 2; and,

FIG. 6 is a bottom plan view thereof.
